UNITED STATES PATENT OFFICE

164,291

CHAIR FRAME

Frederick L. Duer, Bellwood, Ill.

Application July 15, 1949, Serial No. 3,933

Term of patent 14 years

(Cl. D15—1)

To all whom it may concern:

Be it known that I, Frederick L. Duer, a citizen of the United States, residing at Bellwood, in the county of Cook and State of Illinois, have invented a new, original, and ornamental Design for a Chair Frame, of which the following is a specification, reference being had to the accompanying drawing, forming part thereof.

In the drawings:

Figure 1 is a perspective view showing my ornamental design of a chair frame, and particularly, showing in full lines the ornamental form and relative arrangement of the back post-seat support-leg members of said chair frame, the frame companionate seat support-leg member and the frame back rest being shown in dotted lines.

Figure 2 is a front side elevational view of my ornamental design of a chair frame, wherein portions of the back post-seat support-leg members have been broken away and the chair frame back rest is fragmentally shown in dotted lines in supported relation to the back post portions of said members.

Figure 3 is a fragmental top view and horizontal section, taken on the line 3—3 of Figure 2, looking in the direction in which the arrows point.

Figure 4 is an enlarged side elevational view of my said design of a chair frame showing one of its back post-seat support-leg members, with a part of the leg portion thereof broken away; the chair frame companionate seat support-leg member being illustrated in dotted lines in its

operatively assembled relation to the first mentioned member, and the chair frame back rest being illustrated in dotted lines in supported relation to and on the back post portions of the first mentioned member.

Figure 5 is a fragmentary rear side elevation view of the chair frame showing the back post portions of the back post-seat support-leg members thereof, with the chair frame back rest illustrated in dotted lines in supported relation on and to said portions.

The characteristic features of my design reside in those portions shown in full lines in the drawings.

I claim:

The ornamental design for a chair frame, substantially as shown and described.

FREDERICK L. DUER.
